UNITED STATES PATENT OFFICE.

JOSEPH M. BARTON, OF DANVERS, MASSACHUSETTS.

DEVICE FOR USE ON RANDING, HEEL-SHAVING, AND TRIMMING MACHINES.

Application filed May 12, 1921, Serial No. 468,962. Renewed January 8, 1924.

To all whom it may concern:

Be it known that JOSEPH M. BARTON, a citizen of the United States, residing at Danvers, in the county of Essex and Commonwealth of Massachusetts, has invented certain new and useful Improvements in Devices for Use on Randing, Heel-Shaving, and Trimming Machines, of which the following is such a full, clear, and exact description as will enable others versed in the art to which it appertains to make and use the same.

My invention relates to devices for use on randing and heel shaving and trimming machines and more particularly for use on machines designed for shaving rubber or leather heels after they have been attached to the shoe upon which they are to be worn.

My invention has for its objects:—

- 20 1. To eliminate the usual and ordinary difficulties experienced by shoemakers in shaving rubber or leather heels such as are generally used on shoes.
- 25 2. To eliminate the use of oils and other lubricants in the shaving of rubber or leather heels, thus obviating the resulting necessity of removing the same from the rubber or leather after the heels have been so shaved.
- 30 3. To provide an improved revolving, mechanical, adjustable means of guarding the heels so as to insure an absolutely true contour on their finished edge.

- 35 4. To provide a mechanical means of guiding the shaving of heels which will eliminate much of the time heretofore required, increase the output of the operator, and insure a resulting saving to the manufacturer.

- 40 5. To eliminate much of the human element in the machine shaving of heels and avoid much of the dangers and injuries heretofore experienced by heel operators.

- 45 6. To provide an improved means of regulating and adjusting my device.

And to provide other advantages and results some of which are hereinafter referred to.

I accomplish the objects of my invention as illustrated in the accompanying drawings, in which Fig. 1, shows the operating portion of a heel shaving machine upon which my improved guard device is used. Fig. 2, is the view of my improved guard device which faces the cutting knives of the machine upon which it is used. Fig.

3, is a side view of my improved device. Fig. 4, is a top view of the same. Fig. 5, shows the detail of my improved mechanical revolving guard.

Referring again to Fig. 1, 1 shows the fixed portion of my improved guard device. 16, shows the adjustable, revolving, mechanical portion of my improved guard. 2, shows the cutting knife shaft of the heel shaving machine, the cutting knife being shown in dotted lines.

Referring again to Fig. 2, 3 designates the holding screws mounted in a supporting-ring and which fit into the recessed runway 15, on the revolving unit 16, so as to hold said revolving unit securely in its operating position, said supporting-ring being mounted upon and is carried by an adjusting jack 4 by means of which my improved guard and its supporting ring is distanced from the cutting knives 2, (Fig. 1) at the will of the operator by operation of the regulating screw 5, shouldered at 6 and 6', and functioning by means of the threads 7, in the fixed nut 8. Said supporting-ring, and revolving unit or top-lift guard, are adapted to be supported around the cutter-shaft, and the openings through both of these members are greater in diameter than the cutter-shaft to permit lateral adjustment across the axis of the cutter.

Referring again to Fig. 3, 9, shows the tension screw by means of which my improved guard is firmly held at any fixed position after the required adjustment has been made by operation of the regulating screw, 5.

Referring again to Fig. 4, 10, shows the dovetailed unit of my adjusting jack which operates in a similarly shaped slide-way contained in the body portion of my device. Said dovetailed unit is compactly positioned within the slide-way in which it operates by means of the sliding key 12, for the purpose of eliminating the lateral play. 13, designates the holding arm by means of which my improved device is secured to the heel shaving machine upon which it is intended to be used. 14, designates a slot in the holding-arm 13 through which the securing nuts or bolts may be conveniently passed in making my device secure.

Referring again to Fig. 5, 15, shows the recessed run-way formed on a reduced extension of the top-lift-guard and which is engaged by the holding screws 3, shown in

Fig. 2, said holding screws being exposed upon the outside of the supporting-ring. 16, shows the revolving face portion of my improved guard against which rests the top lift of the heel during the shaving process. The revolving face portion 16, is shouldered at 17, so as to prevent any slipping of the heel during the process of shaving.

To those familiar with the art to which my invention appertains it will be understood that heel shaving has heretofore been done on machines provided with revolving knives against which the operator holds the heel he desires to trim while the knives are in operation. Fixed guards have heretofore been resorted to, but to make them usable it was found necessary to smear oil or grease upon the heel before the shaving process and to in turn remove such oils or grease after the shaving was completed. The use of oil or grease caused the heel to slip easily over the fixed guard, whereas my mechanical revolving guard moves easily and steadily in the direction desired without possibility of slipping or danger to the operator. My improved shoulder 17, acts as a double insurance against slipping of the heel or injury to the operator.

Having thus described my invention I claim as new and desire to secure by Letters Patent of the United States of America:

1. In a machine of the class described, a cutter-shaft, a cutter carried thereby, a top-lift guard-support adjustably mounted adjacent said cutter-shaft and provided at one end with a supporting-ring positioned around said cutter-shaft, an endless top-lift-guard having a peripheral recessed runway mounted in said supporting ring, the openings through said top-lift-guard and supporting-ring being of greater diameter than the said cutter-shaft to permit a lateral adjustment across the axis of the cutter, and means mounted in and projecting through said ring and engaging in said recessed runway to retain the top-lift-guard in engagement with the ring and permit its rotation therein.

2. In a machine of the class described, a cutter-shaft, a cutter carried thereby, a dove-tail support mounted to be adjusted parallel with said cutter-shaft, a top-lift-guard support adjustably mounted on said dove-tail support and provided at one end with a supporting-ring positioned around said cutter-shaft, an endless top-lift-guard having a

rear extension formed with a peripheral runway, said extension being mounted within said ring, the openings through said top-lift-guard and supporting-ring being of greater diameter than the said cutter-shaft to permit a lateral adjustment across the axis of the cutter, and means extending through the periphery of said ring and engaging in said peripheral runway to retain the top-lift-guard in engagement with the ring and permit its rotation therein.

3. A device of the character described, comprising a top-lift-guard support constructed to be adjustably mounted on a shoe heel shaving and trimming machine and provided at one end with a supporting ring adapted to be positioned around the cutter-shaft of the machine, an endless top-lift-guard having a portion mounted to rotate inside of said supporting ring, the openings through said top-lift-guard and supporting-ring being of greater diameter than the said cutter-shaft to permit a lateral adjustment across the axis of the cutter, and means extending through the periphery of said supporting ring for retaining said top-lift-guard in engagement with the ring and permit its rotation relative thereto.

4. A device of the character described, comprising a top-lift-guard support constructed to be adjustably mounted on a shoe heel shaving and trimming machine and provided at one end with a supporting-ring adapted to be positioned around the cutter-shaft of the machine, an endless top-lift-guard having a reduced portion mounted to rotate inside of said supporting-ring, said reduced portion forming a shoulder around the top-lift-guard which engages against the faces of the supporting ring, the openings through said top-lift-guard and supporting-ring being of greater diameter than the said cutter-shaft to permit a lateral adjustment across the axis of the cutter, and means exposed at the periphery of the supporting-ring and projecting through the same for retaining the top-lift-guard in engagement with the ring and permit its rotation relative thereto.

In testimony whereof I affix my signature in the presence of two witnesses.

JOSEPH M. BARTON.
